UNITED STATES PATENT OFFICE.

ROBERT A. G. AULT, OF YORK, PENNSYLVANIA.

DESIGN FOR INDENTED PAPER.

SPECIFICATION forming part of Design No. 34,028, dated February 5, 1901.

Application filed December 18, 1900. Serial No. 40,318. Term of patent 14 years.

To all whom it may concern:

Be it known that I, ROBERT A. G. AULT, of York, in the county of York and State of Pennsylvania, have invented and produced a new and original Design for Indented Paper, of which the following is a specification, reference being had to the accompanying drawing, forming part thereof.

The accompanying drawing represents a face view of a piece of paper embodying the present design.

The leading or characteristic feature of the design consists of the two sets of elevations, the elevations of one set being arranged at an angle to the elevations of the other set.

Referring to the accompanying drawing, the letter A indicates the elevations of one set, and B the elevations of the other set, these elevations being arranged at angles to each other.

I claim—

The design for paper herein shown and described.

ROBERT A. G. AULT.
